SPINNING, TWISTING, AND LIKE MACHINE

James Clifford Garnett, Darkfaulds, Blairgowrie, Scotland, assignor of one-half to Baxter Brothers & Company Limited, Dundee, Scotland

Application July 18, 1949, Serial No. 105,357
In Great Britain July 21, 1948

10 Claims. (Cl. 57—54)

1 This invention relates to spinning, twisting and like machines and refers more particularly to the laying of the yarn or other material on to the bobbins, spools or pins.

It has for its chief object to provide improved means for automatically providing a length or tail of yarn on each bobbin or the like during the spinning, twisting or like process, so that both ends of the yarn thereon are available for securing to the outer end of the yarn on another bobbin or the like to facilitate production in subsequent processes.

It has already been proposed in a yarn winding machine to provide bobbins or the like with these tails which are known as "transfer" tails.

In one known arrangement, in order to provide a tail, it has been proposed to provide the barrel of a flanged bobbin with an extension below the bottom flange thereof for the reception of the transfer tail and to provide a device comprising means for holding and driving the bobbin and a guide movable beyond the flange of the bobbin and adapted to carry the yarn over the edge of the flange so as to bring the yarn into contact with the extension and to cause a small amount of yarn to be wound on the extension for use as a transfer tail. The yarn is automatically severed when the tail is formed. In this arrangement the tail forming operation is controlled by movement of a hand lever and requires the attention of an operative.

In another known arrangement for producing a transfer tail on a flanged bobbin in a ring spinning frame it has been proposed to provide the lower flange of the bobbin with a peripheral groove to accommodate the transfer tail and a plurality of grooves formed on the inner face of said flange communicating with the peripheral groove for leading the yarn into and out of the peripheral groove, a series of shallow slots being disposed circumferentially about the flange, these slots serving as means for severing and engaging the yarn when it is held against them at a time when the bobbin is rotating at high speed.

This arrangement is adapted for use with the yarn guiding device hereinbefore referred to as forming part of the first known arrangement. Further in a ring spinning frame it has been proposed to form a transfer tail at the upper end of the bobbin, the arrangement requiring the attention of and manipulation by an operative.

One of the objects of the present invention is to provide means, in a spinning, twisting or like machine, for automatically forming the trans-

2 fer tail on each of the bobbins, severing the yarn to form the tail and holding the severed tail against lashing out under centrifugal action, all these operations being performed automatically without the necessity of stopping the machine or the intervention of an operative.

Another object of the invention is to provide an improved automatic transfer tail-forming and yarn-severing device particularly adapted for use with a spinning or like textile frame of the kind wherein the filled bobbins are doffed and replaced by empty bobbins, the connecting yarn from the previously filled bobbins remaining unsevered while a positive start is being effected on the empty bobbins occupying the same spindle positions as those of the previously filled bobbins, and is subsequently slashed. Heretofore in a spinning frame of the last mentioned type it has been necessary to stop the spinning operation after a start on the new bobbins has been made to allow the slashing of the yarn connecting the filled bobbins in the doffing position with the empty bobbins in the spinning position. This slashing operation is usually done by an operative who proceeds along the frame with a knife and cuts all the yarns as they lie in position over a slasher bar.

Another object of the invention is to render the use of the slasher bar and the hand slashing operation unnecessary.

While the invention is particularly adapted for use with flyer spinning frames it is also adaptable to ring or cap spinning frames.

According to the invention in a spinning, twisting or like frame preferably having doffing mechanism of the kind hereinbefore referred to and wherein the flanged bobbins are carried on holders rotatably mounted on fixed spindles carried on a builder, means are provided for catching the yarn joining an empty or unfilled bobbin in the spinning position and a filled bobbin in the doffing position, during the rotation of the unfilled bobbin by the yarn winding device and leading the yarn so that it is wound round the outer periphery of the lower flange on the unfilled bobbin and is then automatically presented to a severing device.

With this arrangement the yarn is cut leaving a length wrapped round the periphery of the lower flange to form the transfer tail, the spinning proceeding to fill the bobbin in the usual manner.

Means are also provided for catching the tail and preventing it from lashing out under centrifugal action. The formation and severing of

the transfer tail is accomplished automatically without stopping the frame and without the intervention of an operative. In one arrangement according to the invention, a single helical groove is provided on the periphery of the lower flange of the bobbin which as the empty or unfilled bobbin rotates leads the yarn so that it is wound round the outer periphery of the flange. After being wound round the flange, the yarn is caught in a second guide member arranged on the bobbin holder. This second guide means positively guides the yarn into such a position as to present a portion of the yarn under tension to a fixed blade mounted at a suitable point on the builder or on the base of the spindle carrying the holder. In this manner, as rotation of the holder continues the yarn is severed so that a transfer tail substantially of the length of the circumference of the bobbin flange is formed. If desired, the periphery of the lower flange of the bobbin may be formed with a circumferential groove communicating with the helical groove to assist in retaining the transfer tail on the flange during subsequent transit.

This second guide member may consist of a pressed metal cap, secured to the bobbin holder beneath the bobbin, the bobbin seating in a recess on the top of the cap. At a suitable point, the periphery of the cap is cut and slotted to form guide fingers arranged to catch the yarn after it has been wound round the periphery of the flange to form the tail, and to present a portion of the yarn under tension to the fixed blade. The blade may be carried on the usual drag adjuster plate beneath the bobbin holder, or if no drag adjuster is used, on the builder which carries the spindles on which the bobbins are mounted. The cap is arranged to form a guard for the blade.

Further, the above-mentioned guide fingers are so arranged that after severance, the end of the tail is held down and cannot fly outwards or unwrap from the bobbin. Also the second guide member may be formed integrally with the base of the bobbin holder instead of in cap form.

It will be noted that the above-described arrangement includes the formation of an helical groove in the lower flange of the bobbin. In a modification the helical groove is dispensed with and the yarn is caught and guided to the outer periphery of the flange by means of a catch consisting of an upright member fixed in the recess in the aforesaid cap in the clearance between the bobbin flange and the inner wall of the recess and extending up to a point below the upper face of the bobbin flange.

To enable the invention to be fully understood it will now be described by reference to the accompanying drawings which show the invention applied to a flyer spinning frame.

Fig. 1 is a vertical transverse section of one side of a multi-spindle flyer spinning frame showing part of the doffing mechanism, with an empty bobbin in the spinning position before the severance of the yarn connecting it to the previously filled bobbin has been effected;

Fig. 2 is a view in perspective and drawn to a larger scale showing part of a bobbin and bobbin holder having one form of the invention applied thereto, the bobbin being raised on the holder stem to disclose the base of the holder;

Fig. 3 is a side view of the base of the bobbin holder, and

Fig. 4 is a plan view thereof;

Fig. 5 is a sectional elevation showing the bob-

bin holder in position on the spindle of the spinning frame, and

Figs. 6 and 7 are plan views of details of the yarn guiding means applied to the bobbin holder according to the invention;

Fig. 8 is an elevation of the lower part of a modified form of bobbin.

Referring to Fig. 1, the spinning frame illustrated is of known type and is divided into units containing twelve spindles each, the spindles (not shown) being mounted on a builder 10 supported on a carrier 11. A bobbin 12, mounted on a holder, is placed on each spindle and yarn drawn from a roving bobbin 13 is passed to a flyer 14 (one for each spindle) which is driven by the belt 15 from the usual source of power. In operation, the flyers rotate about fixed points and the builder 10 is moved slowly up and down so that the yarn is built up on each bobbin by the respective flyer 14 until the bobbins are filled. The bobbin holders rotate under the drag on the yarn produced by the flyers.

Arranged beneath the builder carrier 11 is a doffing arrangement which comprises end discs 16 (one only being shown) mounted on a rotary shaft 17, the discs being fitted with means for holding a builder carrying empty bobbins and for receiving and holding a builder carrying the bobbins just filled which is lowered from the spinning position, the frame being stopped. This doffing mechanism forms no part of the present invention, the action being briefly as follows: In the position shown in Fig. 1, the builder 10 is in spinning position having been loaded with

empty bobbins 12 and raised. In the doffing arrangement below a builder 18 carrying the previously filled bobbins 19 has been lowered into position, the yarn A being still under control of the flyers 14 and about to be wound round the bobbins 12. The frame is then restarted slowly, to wind yarn A from bobbins 19 onto bobbins 12 to obtain a start on the bobbins 13. At this point the frame is again stopped, connecting yarn A is slashed and the frame restarted. Filled bobbins 19 are then removed and replaced by empty bobbins.

When the bobbins 12 are almost full the set of empty bobbins 20 on a builder 21 are moved by rotation of the shaft 17 to position 20a, this action simultaneously bringing the doffing device into position to receive the builder 10 carrying the full bobbins. The frame is stopped when the bobbins in the spinning position are full and the builder 10 carrying the filled bobbins is lowered on to the doffing device and shaft 17 is rotated to bring the filled bobbins into the full line position previously occupied by the bobbins 19, the fresh set of empty bobbins 20 being simultaneously moved into the position indicated in chain lines, ready for movement up into the spinning position.

It is thought that the above brief description of a well known type of flyer spinning frame will suffice for the understanding of the present invention which is concerned with the means for producing transfer tails on the bobbins used on the spinning frame.

Referring to Figs. 2 to 4. According to the invention, in order to provide for the automatic formation of a transfer tail, the lower flange 22 of each bobbin 23 is formed with an helical groove 24, as shown, this groove leads into a circumferential groove 25 on the outer periphery of the flange, but this groove 25 is not essential and may be omitted leaving the flange simply with an helical groove which will then extend from the upper edge of the flange to a point adjacent to

the bottom edge thereof as shown in Fig. 8. The bobbin 23 is shown as mounted in the usual manner on the stem 26 of the bobbin holder. The bobbin holder is shown more clearly in Fig. 5, and comprises the hollow stem 26 secured to a base 28 and adapted to be slipped over the spindle 29 which is fixed to the builder 30. A drag adjusting plate 31 is mounted on the builder and the portion 31a of the plate 31 makes contact with the base 28 of the bobbin holder. The base 28 is provided with two screw or other pegs 29a arranged on a diameter and adapted to enter two corresponding holes formed on the underside of the base of the bobbin to hold the latter in position.

Referring again to Figs. 2 to 4, A preferably metal cap 32 having a central hole and two diametral holes corresponding to the holes for the pegs 29a in the base 28 is slipped over the shaft 26 of the bobbin holder, the pegs 29a having been removed from the base, and then the cap is turned to bring the peg holes therein into register with the holes in the base and the pegs are replaced securing the cap to the base as shown in Fig. 2. The cap 32 is formed with a recess 33 at the top to receive the base of the bobbin, there being a clearance between the periphery of the base and the wall of the recess.

Fig. 3 shows the bobbin 23 in chain lines in position on the holder with the cap 32 also in position. In order to provide yarn guides the periphery of the cap 32 is cut and slotted to provide three fingers X, Y, Z.

The fingers Y and Z are preferably formed by slitting part of the top of the cap at 34 and bending in parts of the slit metal to form the finger Y integral with the rim of the cap, and the finger Z.

As shown in Figs. 5 to 7 a cutting blade 35 is mounted fixedly in a holder 36 on the side of the drag adjuster plate 31, the holder being also preferably formed with a lip 37 which engages a flange 38 on the bottom of the cap 32 and serves to hold the cap against being accidentally pulled off when the bobbin is removed from the holder. This blade 35 is arranged with its cutting edge facing the direction of rotation of the bobbin holder when it rotates under the action of the flyer. The direction of rotation is indicated by the arrow in Figs. 6 and 7. In setting up the bobbin on the holder it is important that the helical groove 24 in the flange should be closely adjacent to the tip of the finger Y on the cap 32 so that the yarn cannot enter the second guiding means immediately after being caught by groove 24. The tip of the finger Y is preferably slightly raised above the level of the top rim of the cap to ensure that the yarn is caught one revolution after entering the helical groove 24.

This can best be seen in Figs. 2 and 3 and it will be noted that the tip of the finger Y lies between the fingers X and Z with clearances on each side of it. The tip of finger Z is also bent slightly upward to leave a small clearance between it and the tip of finger Y. To assist in assembling the bobbins in correct relation to the caps 32 the parts of the bobbins and caps which should be in register may be painted with similar colours or otherwise distinctively and similarly marked so that registration is rendered simple and easily visible.

Assuming that an empty bobbin and bobbin holder constructed as above described with reference to Figs. 2 to 7 of the drawings is in the spinning position occupied by the empty bobbin 12

shown in Fig. 1 with the yarn A attached to the previously filled doffed bobbin, the operation of the above described arrangement is as follows:

On starting up the frame the flyer proceeds to wind the yarn A on the bobbin which is slowly moving up and down and also rotating with the holder.

As the bobbin rotates the yarn A in being wound onto the empty bobbin 12 from bobbin 19 passes down the bobbin until it is caught in the helical groove 24 in the bottom flange of the bobbin which causes it to twist round the periphery of the flange and when it has completed one turn round the periphery it reaches the finger X and the cap 32. Continued rotation causes the yarn to slip over the top of finger X between it and finger Y and then to rise on finger Z and at the same time to pass between it and finger Y and then to pass beneath finger Y until it reaches the point D (Fig. 3). Further rotation causes the yarn to be stretched between point D and point E in the outer wall of the cap so that a short portion of the yarn is under tension which ensures that it will effectively be severed by the blade 35. Since the bobbin continues to rotate this short portion of the yarn now meets the blade 35 and is severed, leaving a tail of approximately the length of the circumference of the bobbin flange 22. As rotation continues the bobbin is filled up, preventing the tail from unwinding and the free end of the tail is driven by centrifugal force under the finger Z and cannot rise out of the cap 32 and lash about.

If during the formation of the tail part of the yarn should pass under the flange of the bobbin, this does not affect the operation as when the yarn is severed the part under the bobbin will form part of the tail and cannot fly out.

To prevent the yarn passing far under the bobbin flange, thereby reducing the length of tail that would be normally available, the bottom of the recess 33 in the cap may be formed with embossed projections 39 arranged as shown in Fig. 4 which will project up into holes in the bobbin flange and act as stops.

The above operation of the arrangement is not affected by the presence of the peripheral groove 25 in the bobbin flange and the action is as above described if said groove is omitted. Further in a modification the helical groove 24 is omitted from the bobbin flange and an ordinary flanged bobbin is used. All that is required in this modification is to provide a fixed vertical catch member 40 shown in Fig. 3 in the clearance between the flange 22 of the bobbin and the wall of the recess 33. This member 40 extends up to substantially the level of the top of the lower flange of the bobbin when the latter is in position on the holder or it may preferably be slightly lower than this level and it is positioned adjacent to the openings between the yarn guiding fingers X, Y, Z in the cap 32 as seen in Fig. 1. As the bobbin and holder rotate, as already described above, the yarn A which, as will be seen in Figure 1 extends at this time at an acute angle downwards to the filled bobbin 19, is caught by the catch member 40 which causes it to wrap round the flange of the bobbin and to enter between the yarn guiding fingers X, Y, Z by means of which it is guided to the blade 35 and severed, the free end of the tail so formed being held in the cap as in the previously described arrangement. This modified arrangement has the great advantages that standard bobbins can be used without any alteration

to the flanges and the need to locate the bobbins in particular position on the holder in relation to the guide fingers of the cap is unnecessary. It will be noted that in all the arrangements described, according to the invention, the formation of the transfer tail is entirely automatic and there is no necessity to stop the frame in order to slash the yarn by hand as heretofore. Further the transfer tail is automatically limited in length so that yarn wastage in subsequent operation is minimised, and the tail securely held against lashing out and consequent possible destruction under the action of the centrifugal force.

I claim:

1. In a device for winding yarn on to bobbins to form yarn packages having transfer tails and in combination, means for catching the yarn joining an unfilled bobbin in the filling position and a filled bobbin in a doffed position during the rotation of the unfilled bobbin by a yarn winding device and leading the yarn so that it is wound round the periphery of the base of the unfilled bobbin, a yarn severing device, and means mounted below the base of the unfilled bobbin for catching the yarn after it has been wound round the base of the bobbin and leading it under tension to the severing device so that it is severed.

2. In a device for winding yarn on to bobbins to form yarn packages having transfer tails and in combination, a bobbin holder, a bobbin, a flange on the base of the bobbin, a helical groove in the periphery of the bobbin flange extending partially across the flange, a source of yarn supply, a filling means for drawing the yarn from the supply and winding it round the bobbin into the helical groove in the flange thereof and thence round the periphery of the flange, a yarn guide on the holder underneath the base of the bobbin, a fixed cutter blade adjacent to the bobbin holder, means on the yarn guide for catching the yarn after it has been wound round the periphery of the bobbin flange and leading it under tension to the cutter blade so that it is severed.

3. In a device for winding yarn according to claim 2 a peripheral groove formed on the bobbin flange into which the helical groove leads.

4. In a device for winding yarn on to bobbins to form yarn packages having transfer tails and in combination, a bobbin holder, a bobbin, a flange on the base of the bobbin, a helical groove in the periphery of the bobbin flange extending partially across the periphery, a source of yarn supply, a filling means for drawing yarn from the supply and winding it round the bobbin into the helical groove in the flange and thence round the periphery of the flange, a cap secured to the bobbin holder beneath the bobbin, a recess in the top of the cap to receive the base of the bobbin, guide fingers formed in the periphery of the cap, a cutter blade fixed beneath the cap, the guide fingers on the cap being arranged to catch the yarn after it has been wound round the periphery of the bobbin flange and to present it under tension to the fixed cutter blade so that it is severed.

5. In a device for winding yarn according to claim 4 an arrangement wherein the guide fingers

on the cap are also arranged to hold down the severed end of the yarn so that it cannot fly outwards and unwind from the bobbin.

6. In a device for winding yarn according to claim 4, the provision of a cutting blade mounted fixedly in a holder adjacent to the base of the bobbin holder and a peripheral flange at the bottom of the cap, the holder also being formed with a lip which engages said peripheral flange to hold the latter against accidental removal.

7. In a device for winding yarn according to claim 4, the provision on the bottom of the recess in the top of the cap of a series of projections for preventing the yarn from being dragged far towards the spindle beneath the flange of the bobbin during the formation of the transfer tail.

8. In a yarn support adapted to receive a transfer tail the combination of a base flange on said yarn support, a holder on which the support is mounted and a yarn guide comprising fingers formed integrally with the periphery of the base of the holder said fingers being shaped to catch yarn wound around said base flange.

9. In a yarn support adapted to receive a transfer tail the combination of a base flange on said yarn support, a holder on which the support is mounted, a yarn guide cap mounted on said holder, and yarn guiding fingers formed by cutting and bending portions of the periphery of the cap said fingers being shaped to catch yarn wound round said base flange.

10. In a device for winding yarn onto bobbins to form yarn packages having transfer tails and in combination, a bobbin holder, a bobbin, a flange on the base of the bobbin, a source of yarn supply, a filling means for drawing yarn from the supply and winding it around the periphery of the flange on the base of the bobbin, a cap secured to the bobbin holder beneath the bobbin, a recess in the top of the cap to receive the base of the bobbin and providing a clearance between its inner wall and the flange of the bobbin, guide fingers formed in the periphery of the cap, a cutter blade fixed beneath the cap, a fixed vertical catch member disposed in the clearance between the flange of the bobbin and the inner wall of the recess in the top of the cap, said member extending up to substantially the level of the top of the lower flange of the bobbin when the latter is in position on the holder and being positioned adjacent to the openings between yarn guiding fingers in the cap, said guiding fingers being arranged to catch the yarn after it has been wound round the periphery of the bobbin flange and to present it under tension to the fixed cutter blade so that it is severed.
